UNITED STATES PATENT OFFICE

PAUL BALZE, OF LEONIA, NEW JERSEY, ASSIGNOR TO M. & B. MANUFACTURING CO., INC., OF LEONIA, NEW JERSEY, A CORPORATION OF NEW JERSEY

FITTING AND METHOD OF MAKING THE SAME

Application filed July 24, 1929. Serial No. 380,556.

This invention relates to devices that are adapted to be engaged together and to methods of making or engaging such devices.

One object of the invention is to provide a device of the character described, including improved means permitting the device to be constructed to suit any structure with which it is to coact.

Another object of the invention is to provide a device of the nature set forth in which the same has improved means in association therewith which are simple, inexpensive, can be readily, and conveniently applied in the factory or on the job, without necessitating the use of special tools, and which are nevertheless, reliable and efficient in use to a high degree.

A further object of the invention resides in the provision of an improved method of constructing the device, or of engaging the same with any desired structure.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated on the annexed drawings, wherein like parts are designated by the same reference characters throughout the several views.

In the drawings:

Figure 1 is a view in vertical section of a device embodying the invention, showing in dotted lines another form of the same.

Fig. 2 is a top plan view of the device.

Fig. 3 is a view in side elevation showing a step in the method.

Fig. 4 is a view in vertical section showing a completed device embodying the invention and the method of applying the same.

The advantages of the invention as here outlined are best realized when all of its features and instrumentalities are combined in one and the same structure, but, useful devices may be produced embodying less than the whole.

It will be obvious to those skilled in the art to which this invention appertains, that the

same may be incorporated in several different constructions. The accompanying drawings, therefore, are submitted merely as showing the preferred exemplification of the invention.

Generally described, the invention provides a device which is adapted to be engaged with a structure of any given size or shape. In one form of the device, the same includes a body having coacting means that can be changed to suit the said structure. A strong or tight engagement may be made in co-operation with the said means. The engagement may be effected by the use of a material which is fluid or plastic over the means, the latter being readily cut or trimmed to the proper conformation to retain the material referred to. Among the materials may be mentioned lead or other fusible metal, clay or cement, composition materials, and these may be applied under conditions of heat or pressure as the case may require. For the means, sheet material may be employed, made of cardboard, metal, wood, or composition material. The engagement afforded may be either permanent or movable as may be desired, depending upon the shape, or coaction of the engaging parts. The invention is applicable to any device that is to be engaged with or caused to coact with another device whether for purely structural reasons, or to afford a fluid tight connection.

More especially the invention is used in the practice of threaded devices. To illustrate the advantages of the invention, the same may be described in connection with plumbing devices and more particularly clean out plugs. It is customary to provide special couplings which are connected to the plumbing system by the usual bell and spigot joints. These couplings are threaded to receive the clean out plugs. The threads, however, are not standard, so that if a plug should be lost, it would be difficult to replace the same. As a result, leakage of sewage gas would occur. By this invention, the couplings may be closed in a sanitary and approved manner by constructing a plug on the spot to suit the individual coupling.

Referring in detail to the drawings, 10 de-

notes a device embodying the invention. The same includes a body 11 which may be of any suitable size or shape. The same may be in the nature of a core that is made of any material that is feasible for the purpose. The said core can be made of a metal such as cast iron, and it is of circular form. It is surrounded by an engagement portion or head 12 for manipulating the plug.

Secured in any suitable manner to the bottom of the core is a sheet of material 13 which extends beyond the edge of the core, and may lie in any required relation thereto. Thus the said sheet is disposed in a plane at right angles to the axis of the core. It may consist of any suitable material, as, for example, cardboard. The latter may be fixed to the core by pins 14 which are driven with a close fit into holes 15 drilled or otherwise formed in the core 11. Although the member 13 is shown as being in the shape of a disc, it will be understood that it may have any other shape that might be required. The diameter of the disc is considerably larger than that of the core, and it may have any desired ratio thereto.

16 denotes a structure with which the device 10 is adapted to be engaged. Said structure may be any conventional fitting or a coupling having at its lower end a spigot 17 and being internally threaded at its upper end at 18. The thread referred to may be of any kind whatsoever.

In practice the device 10 is placed on the coupling 16 with the member 13 resting on the upper edge of the coupling and being of greater diameter than the same. With the core 11 positioned in coaxial relation to the said coupling, the operator applies a hammer to the member 13 and causes a circle to be impressed therein, either completely severing an outer annular portion 13a of the member 13, or else cutting the said ring portion by the application of a suitable cutting tool. The member 13 is then screwed into the thread 18 to any desired extent. Being of a yielding or pliable material, it will readily adjust itself to the thread and make a tight closure in the coupling, especially in view of the taper of the thread. The operator now pours a fused metal, such as molten lead, into the coupling above the closure member 13 and into the annular space between the core and the wall of the coupling. This metal solidifies rapidly and assumes the ring shape of the said annular space, including the threads 18. The ring 19 of relatively soft, rust proof metal thus formed is strongly fixed to the core by any suitable projections 21 extending from the core. It is thus seen that a new and unitary plug 22 is constructed to fit the coupling 16.

By this invention, the plug 22 can be constructed on the job to suit any particular type of coupling or thread. The plug is remov-

able and can be used in the customary manner. It is rust proof and affords a tighter connection with the coupling than can be obtained with a threaded plug. By making the closure disc sufficiently large, a comparatively small number of sizes of the device 10 need to be carried in stock.

Although the invention has been shown as applied to a plug and coupling, it can be used also with devices of other kinds, and the drawings herein are therefore to be considered as illustrative and not in a limiting sense.

It will thus be seen that I have provided a device which fulfills the several objects of the invention and is well adapted to meet the conditions of practical use.

I claim:

1. A device of the character described, including a plate of fibrous material that is adapted to be cut to any desired form or size, and a coaxial core extending upward from the plate with the latter extending laterally beyond the core to afford a circular space open in axial direction.

2. The method of constructing a fitting in situ, which includes engaging a disc to the bottom of a core, the disc being larger than the core and aligned therewith, cutting the disc down to fit the thread of a hollow member, threading the disc into the said thread with the core extending upward to form an annular upward opening space about the core in the hollow member and with the core supported by the disc, and placing a fusible material into the said space through said opening to set with a thread in engagement with the thread of the hollow member and with the solidified material in engagement with the core, whereby an integral fitting is produced accurately conforming with the thread of the member and removable therefrom.

In testimony whereof I affix my signature.

PAUL BALZE.
